CLAIM

The ornamental design for a system controller enclosure, as shown and described.

DESCRIPTION

FIG. 1 is a perspective view of a system controller enclosure depicting an embodiment of a new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.

The broken line portion of the figure drawings is included to show unclaimed subject matter only and forms no part of the claimed designs.

1 Claim, 4 Drawing Sheets(56)
